ENGINE STARTING DEVICE

Nicolas Herzmark, Paris, France

Original application February 4, 1931, Serial No. 513,437. Patent No. 2,035,161. Divided and this application November 1, 1935, Serial No. 47,858. In France February 4, 1930.

4 Claims. (Cl. 121—37)

This invention relates to fluid pressure operated starters for internal combustion engines and other motors, of the type comprising two pistons located in a fixed cylinder formed by the casing 5 of the starter and between which pistons the compressed air or gas is admitted.

The present invention (which forms a division 10 of my pending application Serial No. 513,437, filed February 4, 1931, and issued as Patent No. 2,035,161 on March 24, 1936) has for its main object to reduce the size or bulk of the starter, or for the same size to increase the maximum 15 number of turns which the starter can make in a single starting operation.

15 The invention also comprises a particular arrangement of the starter permitting its interior parts to be easily withdrawn from the casing, with a view to their inspection or replacement, without it being necessary to take down the pipes 20 connecting the starter with the reservoir of compressed air or other fluid under pressure.

The invention has for a further object to ensure the accurate positioning of the pistons, when they are automatically drawn together after 25 the operative stroke of the starter, in readiness for the next operative stroke.

One form of carrying out the present invention, given solely by way of example, is hereinafter described with reference to the accompanying 30 drawing, which is a longitudinal axial section of a preferred construction. In this drawing, the casing *a* of the starter is fixed by any suitable means as by bolts (not shown) upon the engine or upon the chassis supporting the engine. The 35 casing *a* is provided at its front end (remote from the engine) with an annular member *b* of which the interior surface *b*¹ is screw-threaded. In the interior of the casing *a*, which forms the fixed cylinder to which the air is admitted, are two 40 pistons *c* and *d*, fitted with packing leathers *c*⁰ and *d*⁰ or similar elastic packing members, held in position by rings *c*¹ and *d*¹ secured by screws *c*² and *d*². The piston *c*, which is the driving piston, is fast with a socket or sleeve *e*, the exterior surface *e*¹ of which is screw-threaded in such a manner as to be able to screw through the annular member *b*. This member *b* forms a quick-pitch nut. The other end of the sleeve *e* is also provided on its interior face with a nut *f*. 45 The other piston *d*, which is displaceable through only a limited stroke, is fixed by means of a circular nut *d*³ upon an inner socket or sleeve *g*, also screw-threaded on its exterior surface *g*¹ and adapted to screw through the nut *f*. 50 The end of sleeve *g* adjacent to the engine to be

started is fitted with a coupling member *g*² having ratchet jaws and coming into engagement, at the time of starting, with the corresponding member *g*³ keyed upon the shaft of the said engine.

These screw-threaded members *e* and *g* are 5 normally (i. e. when in the inoperative position) telescoped one within the other. The nut *f* is at the end of the sleeve *e* opposite to the nut *b*. It will also be noted that the outer sleeve *e* is directly attached to piston *c* whilst the inner 10 sleeve *g* is directly attached to the piston *d*.

A tension spring *h*, connecting the inner end of the sleeve *g* with the outer end of the sleeve *e*, is intended to bring back the pistons *c* and *d* substantially into contact after the operative stroke 15 of the starter, in order to restore the parts to the position for another operation. As shown in the drawing, the edge of a flange *d*^x formed on the piston *d* abuts directly against the screw-threaded boss of the piston *c* to limit the return 20 movement and thus ensure maintenance of a pre-determined spacing between the pistons for the admission of pressure fluid.

A pipe connection *i* leading to the fluid pressure (such as compressed air) supply line is 25 designed to admit the fluid under pressure into the casing or cylinder *a* at a point between the two pistons *c* and *d*. A suitable cock or valve (not shown) controls the admission of the compressed air or fluid into pipe connection *i*.

A number of balls *j* are spring-pushed against the cup-seatings *j*¹ formed on the exterior surface of the sleeve *e*, so that this sleeve and consequently the piston *c*, will experience a certain resistance to their axial displacement at the beginning of such movement.

The working of the arrangement is the following:—

When compressed air or gas is admitted between the two pistons *c* *d* by the appropriate operation 40 of the aforesaid cock or valve, the piston *d*, which is entirely free, is displaced towards the member *g*³; the sleeve *g*, with which piston *d* is fast, screws through the nut *f* which for the moment is stationary. The jaw coupling *g*² comes 45 into engagement with the coupling *g*³, and the piston *d* is thereupon stopped.

Under the force derived from the compressed air acting on the piston *c*, the balls *j* are now 50 pushed back out of the cups *j*¹, and the driving piston *c* moves axially whilst revolving as the sleeve *e* screws through the nut formed by the member *b*. At the same time, the nut *f*, fast with the travelling and revolving sleeve *e*, causes the screw-threaded sleeve *g* to turn, which conse- 55

quently imparts a movement of rotation to the coupling members g^2 and g^3 and thence to the motor shaft.

It will be seen that when the sleeve e has made 5 one complete turn and has consequently advanced one screw-pitch, the interior sleeve g has also performed one complete revolution relatively to the sleeve e and therefore has made two complete turns relatively to the fixed part b . This obviously is on condition that the screw threads of 10 the two sleeves e and g are of equal pitch but of opposite hand or direction. The result of this arrangement is that the number of turns of the central sleeve g and therefore of the shaft to be 15 started, is double that which would be obtained with a single screw-threaded sleeve.

It will be noted that the movement of driving piston c away from piston d applies driving torque to the engine to be started. It is also to 20 be noted that the pistons c d move in opposite directions when compressed air has been admitted at i and that both these pistons are guided by the bore of the cylinder casing a . After 25 the engine has been started, the fluid pressure is relieved and the spring h returns the parts to their normal positions.

In order to provide for dismounting the starter without having to disconnect the compressed air pipes, the inner cylinder head l of the starter is 30 fixed to the cylinder a by screws or the like m entering a groove n , and the outer end or annular member b is screwed into the said cylinder. Consequently, when it is desired to withdraw from 35 the cylinder or casing all the components of the starter, it is sufficient to unscrew the screws m and the annular member b .

Instead of compressed air to separate the pistons, I may employ gas under pressure, and such gas may be obtained from a storage tank or directly from an explosion (such as that of a cartridge) 40 conveyed into the inlet i .

The invention is not limited to the form of construction which has been described but can be carried out with all modifications based on the 45 same principle. The starter can likewise be combined with an air compressor mounted on the same axis and driven by the motor shaft. For this purpose, the rear end of the starter casing or cylinder barrel a , as shown in the drawing, is provided with a centering portion or register l' in which the extremity of the compressor casing can be located in alignment with the starter and the engine shaft.

What I claim is:—

55 1. An engine starter comprising a fixed cylindrical casing; a stationary apertured closure member at one end of said casing, the walls defining said aperture being threaded; an end plate slidable throughout the length of said casing and adapted normally to close the other end of said casing; a pair of opposed pistons of equal diameter and reciprocable within said casing; means for introducing fluid under pressure between the pistons to move the pistons in opposite directions 60 towards the apertured closure member and the end plate respectively; an outer sleeve within said cylindrical casing having external and internal threads, the external threads adapted to engage the threads of the stationary apertured closure member and to be rotated thereby, said sleeve being directly connected to one of said pistons and being protrusible in part from said cas- 65

ing through the apertured closure member; an inner sleeve within the outer sleeve having threads to engage the internal threads of the outer sleeve to be rotated thereby, said inner sleeve being secured directly to the other of said pistons; and a clutch element secured to one end of the inner sleeve and engageable with a clutch element of the engine to be started, whereby the rotation of said sleeves is imparted to the engine, the screw-threaded portion of said inner sleeve 10 being normally within the length of the outer sleeve. 5

2. In an engine starter, a fixed cylindrical casing, a pair of pistons of equal diameter slidable in said casing, means for admitting pressure fluid 15 between said pistons to move them in opposite directions, a screw-threaded sleeve secured to one of said pistons, a stationary nut co-operating with said sleeve at one end of said casing, an apertured end plate slidable throughout the 20 length of said casing and adapted normally to close the other end of said casing, an inner sleeve secured to the other of said pistons, said inner sleeve having screw engagement with the first mentioned sleeve for rotating said inner sleeve 25 by movement of the first mentioned sleeve, and means secured to said inner sleeve for engaging an engine shaft. 25

3. In an engine starter, a fixed cylindrical casing, a stationary apertured closure member at one 30 end of said casing, the walls defining the aperture being threaded, an apertured end plate slidable throughout the length of said casing and adapted normally to close the other end of said casing, a pair of pistons of equal diameter slidable in said casing, means for admitting pressure fluid between said pistons to separate them by movement in opposite directions, an internally and externally screw-threaded sleeve secured to one of 35 said pistons, said sleeve adapted to screw its external threads through the threaded aperture in said closure member, an inner sleeve secured to the other of said pistons, said inner sleeve having external screw threads co-operating with the internal threads of the first mentioned sleeve for 40 rotating said inner sleeve by movement of the first mentioned sleeve, and means secured to said inner sleeve for engaging an engine shaft, said inner sleeve having limited axial movement 45 through the aperture in said end plate. 50

4. In an engine starter, a fixed cylindrical casing, a pair of pistons of equal diameter slidable in said casing, means for admitting pressure fluid between said pistons to move them in opposite directions, a screw-threaded sleeve secured to one 55 of said pistons, a stationary nut cooperating with said sleeve at one end of said casing, an apertured end plate slidable throughout the length of said casing and adapted normally to close the other end of said casing, an inner sleeve secured to the other of said pistons, a nut holding said other piston upon said inner sleeve, said nut extending outside the aperture in said end plate, means for rotating said inner sleeve by movement of the 60 first mentioned sleeve, and means secured to said inner sleeve for engaging an engine shaft, the return movement of said pistons after completion of a starting operation being limited by the abutment of said nut with said end plate and by the 65 abutment of said pistons against one another. 70
